TYPE ACTION SYSTEM FOR TYPEWRITING MACHINES

Harry C. Yaeger, West Hartford, Conn., assignor to Underwood Corporation, New York, N. Y., a corporation of Delaware

Application December 11, 1951, Serial No. 260,960

6 Claims. (Cl. 197—27)

1

This invention relates to typewriters and the like and more particularly to type-action systems thereof having the type bars pivoted in an articulate array on a segment to strike at a common typing point, and wherein case shift is effected by shifting the type-bar segment.

In type-action systems to which the invention pertains, each type bar is actuated by a straight link or pull rod extending forwardly beneath the type bar from its point of connection to an operating arm of the type bar. In segment-shift typewriters the segment is usually shifted in a plane that is tangential to the platen at the typing point. In order not to transmit any perceptible motion to the key levers nor change the operating relation of the parts during case shifting, these pull links are usually arranged substantially at right angles to said plane of shift. Each pull link is connected at its forward end to an actuating member, which in the Underwood typewriter takes the form of a sub-lever, as exemplified in Helmond patent, No. 2,072,878, for manual typewriters, and in Yaeger patent, No. 2,254,764, for power-operated typewriters. As shown in said patents, the type-action pull links assume substantially horizontal positions in accord with the substantially vertical plane of case shift and are therefore at or very close to a parallel relation with the horizontal type bars. In typewriters wherein the segment shifts in a vertical plane, this is due mainly to the fact that the typing point is at a level with the platen axis, and the plane of shift is required to be tangential with the platen at said point. Should it be desired to have the typing point appreciably above the level of the platen axis, it then becomes necessary to correspondingly tilt the type-bar segment so that its plane of shift is tangential at said raised typing point, the type bars at rest being also correspondingly inclined. The resultant inclination of the type bar dissolves its parallel relation with the pull link, unless the position of the latter is also to be substantially changed. Thus, if it is necessary to discontinue this substantially parallel relation between the type bar and its operating link, either to raise the typing point appreciably above the level of the platen axis without changing the horizontal position of the pull link, or to afford an appreciable angular space relation between these parts for reason such as to accommodate a type bar that is arched to clear a dust shield on the segment, this disturbs the fundamental relation of the type-action elements and this in turn materially upsets the inter-relation of the type-action

2

system with the direction or path of case shift.

Accordingly, a general object of the invention is to provide, in a segment-shift, hammer type-bar kind of typewriter, an arrangement of the type-action system and a case-shift guiding means coordinated therewith, which arrangement affords a substantial angular relation between the quiescent type bars and their underlying pull links.

Another object is to provide a segment case-shift arrangement coordinated with an improved type-action system, the organization and arrangement of the elements of the latter having the advantage of accommodating an appreciably inclined segment for purposes such as to secure a typing point well above the level of the platen axis, the related tilting of the type bars being readily feasible without however necessitating any major change in the arrangement of other type-action elements, particularly the substantially horizontal disposition of the underlying pull links.

In prior segment-shift typewriters, the necessity of shifting the segment downward to effect case shift presented a condition which, because of the substantially parallel close relation of the quiescent type bars and their pull links, made it impracticable to provide the requisite dust shelf on the segment, because of the lack of space clear of the links necessary to accommodate bowed or arched type bars required to clear the dust shelf.

A further object, therefore, resides in the provision of a correlated type-action system and segment shift arrangement, by which adequate spacing between the type bars and their straight operating links is had, so that the downwardly case-shifted type bars, arched so as to clear a segment-carried dust shield, will not clash with or obstruct proper operation of the type-action links.

Other objects will be in part obvious and in part particularly pointed out as the following description of a preferred embodiment of the invention proceeds.

In the drawings:

Figure 1 is a sectional view taken on a medial plane fore-and-aft of the typewriter embodying the invention, and showing a middle type action and another type action at the far side of the type-action system.

Figure 2 is a plan view of the type-action system taken on a plane 2—2 of Figure 1, but viewing only the half of the type-action system opposite that shown in Figure 1, and

Figure 3 is a front view of the type-action system taken on a line 3—3 of Figure 2.

Except for the relative arrangement of several of the series of type-action parts as hereinafter explained, the type-action system forming the illustrated embodiment of the invention conforms substantially to that described and claimed in the Helmond patent, No. 2,072,878. A brief description of the type-action system herein will therefore suffice. Referring to Figure 1 a series of key levers 5, the forward key-equipped portions of which are omitted, are each pivoted on a common fulcrum rod in a crossbar 6 of the typewriter. At a point intermediate its end, each key lever 5 is connected by a link 7 to a sub-lever 8. The sub-levers 8 are all pivoted on a common fulcrum rod retained in a crossbar 10.

A series of type bars 11 are each pivoted in an arcuate array on a pivot rod 12 in the segment 13. Each type bar 11 has an operating arm 14 extending rearwardly and downwardly from the pivot 12 and having a connection 15 to a pull link 16, the other end of which is connected at 17 to a corresponding one of the sub-levers 8.

In view of the arcuate arrangement of the type-bar pivots 12, the connections 15 to the links 16 also present a curved or arcuate formation, see Figure 3. The lower portion of each sub-lever 8, where same is pivoted in the crossbar 10, is disposed vertically in the plane of the associated key lever 5. This makes the row of sub-levers 8 appreciably wider, transversely of the typewriter, than the array of the type-bar-link connections 15. Therefore, the successive sub-levers 8 are bent to offset their upper ends at gradually increasing extents, ranging from the center type action outward, so that said ends at which the links 16 are connected are close to the plane of the corresponding operating arms 14 of the type bars. To assure a uniform length for the links 16, and to attain certain operating advantages incidental to case shifting, the upper end portions of the sub-levers 8 forming the link connections 17 present an arcuate array conforming substantially to that of the link connections 15 and circumjacent thereto, as shown in Figure 3, and each of said end portions is disposed in a plane radiating from the typing point as later described. As described in detail in said Helmond patent, the points of connection of the links 7 to the sub-levers 8 are arranged at gradually increasing distances from the sub-lever pivot, ranging from the center type action outward, to assure a uniform stroke for each type bar 11. Likewise, the points of connection of the links 7 to the key levers 5 are at graded elevations increasing from the center outward.

As afore-stated, the sub-levers 8 may be either manually operated, as shown in said Helmond patent, or may be power operated, for example, as shown in said Yaeger patent, No. 2,254,764. In its broader aspect the sub-lever 8 of each type action constitutes an actuating member thereof, in that the manner of actuating the pull link 16, whether by a sub-lever as shown, or by other actuating means, is not important to the practice of the invention. It is however essential that the connection points 17 of the actuating members be positioned to accommodate the prescribed arrangement of the links, as later described.

The type bars 11 when inactive assume the positions shown in Figure 1 with their forward ends lying against a usual type-bar rest, not shown, which is supported on the segment 13 to move the entire type-bar basket therewith in case

shifting. The type bars 11 are guided by the usual radial slots 18 in the segment, Figure 3, to strike at a common typing point indicated at T in Figures 1 and 3. The usual type guide, not shown, may serve to further guide the type so as to strike accurately at said point. It may be here noted, with reference to Figure 1, that the typing point T in the embodiment shown is at the point of tangency of a line in a central vertical plane fore-and-aft of the typewriter, tangent with the platen 20 and extending through or relatively close to the axis of the pivot rod 12. Said typing point is further indicated as being at the intersection of a construction line A with the periphery of the platen and passing through the platen axis.

Erasures made on the work sheet resting against the platen 20 result in much of the eraser dust falling against the segment 13 and lodging to a large extent in or about the pivot slots 18 where an accumulation becomes detrimental to proper operation of the typewriter. To prevent the eraser dust from reaching the type bar pivotal mounting, a shelf-like projection or dust shield 22 is provided. This dust shelf is just above the array of pivot slots 18 and may be arcuate and concentric with the pivot rod 12. In order to clear the dust shield 22 as the type strikes the platen, the type bar 11 is substantially arched as indicated at 23. Because of the closeness of the dust shelf 22 to the pivotal mounting of the type bars, it is necessary that the arched portion 23 start abruptly just beyond the type-bar pivot, at which portion, also, a shoulder 24 of the type bar is arranged to engage a universal bar 25 for operating the letter-feed mechanism. The abruptness and close proximity of the arched portion 23 to the type-bar pivot 12 makes the problem of clearance between each type bar and its pull link 16 more acute, since the outer edge of the type bar at said arch bows out appreciably from the body of the type bar.

In the embodiment of the invention illustrated, the means for guiding the segment 13 for case-shift movement, except as to certain features of arrangement hereinafter set forth, is like that described and claimed in the Helmond patent, No. 2,306,604, to which reference is had for details not shown herein. As is the usual practice, the segment 13 is normally suspended by spring means, not shown, in its upper position in which the type of the lower case on the type bars 11 are adapted to strike the typing point T, and from which the segment is shifted downwardly to cause the other or upper case of type to strike at said point. The segment 13 is secured to a segment frame 27, the upper portion of which is guided for case-shift movement by a ball-and-raceway unit 28 at each side of said frame. Said units each comprise raceways respectively on the segment frame and on a member 29 of the typewriter mainframe. The two ball-and-raceway units 28 constitute guiding means for the upper part of the segment, causing said part to move in a path indicated by the line 30 in Figure 1, as later described.

The segment frame 27 has at each side thereof a downwardly reaching leg 31, Figure 1, on each of which a roller 32 is rotatably mounted. Each roller 32 rides between front and rear guide faces 33 of a member 34, and each of said members is secured to a crossbar 35 of the typewriter. The rollers 32, the members 34 and the crossbar 35 constitute a guiding means for the lower portion of the segment, by which the axis of said roller

is caused to follow a path indicated by the line 36, later described.

To assure equal movement of each lateral portion of the segment frame during case shifting, a bail 38 is provided, a cross-shaft 39 of which rigidly connects the two arms 40 and is pivoted at 41 on the typewriter mainframe. Since the segment frame 27 moves in a path not concentric with the axis of pivots 41, a sliding connection between the bail arms 40 and the segment frame is provided. This may take the form of a shoe 42 rockably secured to each bail arm and slidable in a groove in each lateral edge of the segment frame. Thus, the bail 38 will cause the segment frame to case shift with a parallel motion and yet will not influence the direction of case-shift movement, this being the combined function of the upper guiding means 28 and the lower guiding means 32-35.

The mechanism for actuating the type-bar segment 13 in case shift may be of any suitable kind. That shown herein in Figure 1 comprises a shift key lever 43 similar to the key lever 5 but having a hook portion 44 which engages a stud 45 on a shift arm 46. The shift arm 46 is pivotally mounted at its forward end, the other end being operatively connected by a link 47 to the leftward leg 31 of the segment frame 27. Depressing shift key lever 43 will cause the shift arm 46 to swing clockwise about its pivot and thus shift the type-bar segment downward.

The present invention provides a type-action system arrangement and a segment case-shift guiding means coordinated therewith, by which an appreciable angular spacing is afforded between the type bar 11 as a whole and its pull link 16. From one aspect, this enables disposing the type-bar segment at an appreciable angle consistent with a typing point that is substantially above the level of the platen axis, and yet permits the links 16 to remain at about their horizontal positions. Or if desired, the principles of the invention will accommodate an arrangement of the pull links 16 that inclines substantially downwardly from the connection 15 of the type bar, while maintaining the type bar in its previous horizontal position and the segment in its approximately vertical position consistent with a typing point that is about at the level of the platen. The arrangement of the elements of the type-action system, particularly the segment 13 and the links 16 as illustrated in Figure 1, is in effect a combination of these features of arrangement. That is, the segment 13 is disposed at an appreciable angle from the vertical, and the links 16 are inclined somewhat from the horizontal.

From another aspect, the provision of an appreciable angular spacing between the type-bar lever and its pull link 16 has the advantage of accommodating bowed or arched type bars and thus enables the use of the dust shelf 22, in a segment-shift typewriter. As before mentioned, the close proximity of the arched portion 23 to the type-bar pivot 12 causes the type bars, particularly at or near the center of the machine, to project into the region heretofore occupied by the pull links in their substantially parallel relation to the type bars.

As shown in Figure 1, the link connections 15 to each of the type-bar operating arms 14 move in a generally up-and-down direction during case shifting, and this movement in turn causes each of the straight pull links 16 to oscillate between the two positions shown respectively in

full and dot-and-dash outline. The construction line B relates only to the link 16 of the medial type action. Said line bisects the angle of vibration of that link 16 and thus indicates the center-line of oscillation of said link, intersecting the pivotal point 17 and extending rearwardly therefrom. Line B' is a construction line similar to line B except that it relates to the link 16 associated with the outermost type action of the system. The construction line B' shown in Figure 2 is the same as the line B' shown in Figure 1 except that it relates to the outermost type action at the opposite or right side of the typewriter. In Figure 3 the line B² is a construction line like line B but relates to a type action intermediate the medial and outermost type actions.

It will be recalled with reference to Figure 1 that the construction line A extends from the typing point T rearwardly through the axis of the platen 20. It will be noted with reference to Figure 2 that said line A is in a central vertical plane fore-and-aft of the typewriter. Said line A extends rearwardly to a point of convergence C, at which point the lines B, B' and B² relating to the links 16 of all the type actions converge. It will now be seen, in view of the arcuate arrangement of the link connections 17 to the sub-levers 8, that the lines B, B' and B² extending from all of the connections 17 to the point of convergence C, collectively form a conical contour. The apex of the cone thus formed is at the point C and the line A is the center-line or axis of the cone.

A horizontal line D, Figure 2, at right angles to the line A and passing through the point of convergence C, defines an axis which forms the basis for coordinating the case-shift guiding means with the type-action system and with the typing plane on the platen. That is to say, the means for guiding the segment 13 in case shift is so arranged with respect to the pull links 16 of all of the type bars 11 that the points of connection 15 move in prescribed paths such as will avoid the transmission of any motion to the sub-levers 8 and thence to the key levers 5. The arrangement of the segment-guiding means further assures that both cases of type on the type bars 11 will approach the typing point, to strike the platen, on a line radial with the axis of the platen at said point.

To accomplish this coordination, the segment 13 during case shift moves in an arcuate or cylindrical path, the curvature of which is concentric with the axis D which, as stated, coincides with point of convergence C. Since the shift movement of the segment is determined by the upper guiding means 28 and the lower guiding means 32-35, it follows that the paths of travel generated by these guide means, respectively, are concentric with said axis D. That is, with respect to the two upper guide units 28 at the sides of the segment, the line of travel 30 determined by each unit 28 is an arc struck from the center or axis D. Likewise, with respect to the two lower guide units 32-34 at the opposite sides of the segment frame, the line of travel 36 determined by the guide faces 33 of each lower unit is an arc, the center of which is the axis D.

By causing the segment 13 to case shift in a cylindrical path concentric with the axis D on which the point C lies, the connection points 15 of each pull link 16 will be caused to move in paths also concentric with the axis D. In that the center-line of oscillation B, considering only the central type action for example, radiates

from the point C, it follows that the path taken by that connection 15 is substantially normal to, or at right angles with, said line B. It will be seen that said path coincides substantially with an arc struck from the point 17, through the upper and lower positions of point 15, and that therefore practically no motion will be transmitted through link 16 during or incidental to the case-shift movement of point 15. With regard to the typing point T on the platen 20, it follows that, because the segment moves in a path concentric with the axis D, and because of the fact that the line A passing through the platen axis and the typing point radiates from the point C on axis D, both the upper and the lower case of type will approach the platen on the radial line A and will meet the platen on a plane tangential thereto at the typing point.

Considering the very short extent of case-shift movement, about one quarter inch in most typewriters, particularly in relation to the large radius of curvature of the path of point 15, taking the medial type action for example, it will be seen that said path as generated by the upper and lower guide means respectively may be in a straight line. It is necessary, however, that said straight line path be at right angles to the line B. This result will be had if the path 36 described by each lower guide means 32-35, instead of being a curve from the axis D, be on a straight line which forms a chord of said arc, intersecting the upper and lower points defining the two positions of the axis of roller 32. The same applies as to the path 30 of the upper guide means 28. That is, instead of being curved on the axis D, said path may lie in a straight line which forms a chord of the arc described by said curve. By having the point 15 move in a straight line path, related to the axis D as described, said path will coincide more closely with the arc struck from point 17.

While the above description is confined to the effect of the arrangement of the case-shift guiding means on the central type action, particularly with reference to the link 16 and the construction line B thereof, it will be apparent that a similar effect is had for all the type actions. That is, the points 15 of the other links 16 throughout the entire type-action system will move in like paths having a similar relation to their respective construction lines B' and B², since all said construction lines converge on the point C and since said point is on the axis D upon which the path of movement of the type-bar segment is based.

Having thus described the invention, what is claimed is:

1. In a typewriter type-action system, a cylindrical platen, a series of type bars each having an operating arm, means including a segment pivotally mounting said type bars to strike at a common typing point on the platen, a series of straight pull links connected respectively to said type-bar operating arms, the arrangement of said operating arms and said pull links with respect to the body of the type bars when inactive being such that said pull links are relatively close to and beneath the body of the corresponding type bars, means for guiding said segment in case-shift movement, and a series of actuating members connected to the forward ends of said pull links, said actuating members being non-case-shiftable, said pull links therefore oscillating during case shift to accommodate the shift movement of the type bars, each link having a con-

struction line extending from its point of connection to the actuating member and bisecting the angle of oscillation, the arrangement of all the links being such that their construction lines converge substantially at a common point, said point of convergence lying in a fore-and-aft center-line of the typewriter extending from the typing point and intersecting the axis of said platen, said point of convergence also lying in a horizontal axial line normal to said center-line, said case-shift guiding means being adapted to guide the segment in a path substantially concentric with said axial line.

2. In a typewriter type-action system, a cylindrical platen, a series of type bars each having an operating arm, means including a segment pivotally mounting said type bars in a curved array to strike at a common typing point on the platen, a series of straight pull links connected respectively to said type-bar operating arms, the arrangement of said operating arms and said pull links with respect to the body of the type bars when inactive being such that said pull links are relatively close to and beneath the body of the corresponding type bars, means for guiding said segment in case-shift movement, and a series of actuating members connected to the forward ends of said pull links, said actuating members being non-case-shiftable, said pull links therefore oscillating during case shift to accommodate the shift movement of the type bars, each link having a construction line extending from its point of connection to the actuating member and bisecting the angle of oscillation, the arrangement of all the links being such that the construction lines thereof collectively define a conical contour, the apex of the cone being in a center-line of the typewriter extending rearwardly from the typing point and intersecting the axis of said platen, said cone apex substantially coinciding with a horizontal axial line normal to said center-line, said case-shift guiding means being arranged to guide the segment in a path substantially concentric with said axial line.

3. In a typewriter type-action system, a cylindrical platen, a series of type bars each having an operating arm, means including a segment pivotally mounting said type bars in a curved array to strike at a common typing point on the platen, a series of straight pull links connected respectively to said type-bar operating arms, the arrangement of said operating arms and said pull links with respect to the body of the type bars when inactive being such that said pull links are relatively close to and beneath the body of the corresponding type bars, separate means for guiding respectively the upper portion and the lower portion of the segment in case-shift movement, and a series of actuating members connected to the forward ends of said pull links, said actuating members being non-case-shiftable, said pull links therefore oscillating during case shift to accommodate the shift movement of the type bars, each link having a construction line extending from its point of connection to the actuating member and bisecting the angle of oscillation, the arrangement of all the links being such that their construction lines converge substantially at a common point, said point of convergence lying in a center-line of the typewriter projecting rearwardly from the typing point and intersecting the axis of said platen, said point of convergence also lying in a horizontal axial line at right angles to said center-line, each of said segment guiding means defining paths of movement for

the respective portions of the segment that are cylindrical and concentric with said horizontal axial line.

4. In a typewriter type-action system, a cylindrical platen, a series of type bars each having an operating arm, means including a segment pivotally mounting said type bars in a curved array to strike at a common typing point on the platen, a series of straight pull links connected respectively to said type-bar operating arms, the arrangement of said operating arms and said pull links with respect to the body of the type bars when inactive being such that said pull links are relatively close to and beneath the body of the corresponding type bars, separate means for guiding respectively the upper portion and the lower portion of the segment in case-shift movement, and a series of actuating members connected to the forward ends of said pull links, said actuating members being non-case-shiftable, said pull links therefore oscillating during case shift to accommodate the shift movement of the type bars, each link having a construction line extending from its point of connection to the actuating member and bisecting the angle of oscillation, the arrangement of all the links being such that their construction lines converge substantially at a common point, said point of convergence lying in a center-line of the typewriter projecting rearwardly from the typing point and intersecting the axis of said platen, said point of convergence also lying in a horizontal axial line at right angles to said center-line, each of said segment guiding means defining paths of movement for the respective portions of the segment that are each normal to a plane intersecting said horizontal axial line and midway of the limits of case shift at each portion.

5. In a typewriter type-action system, a cylindrical platen, a case-shiftable segment, a series of type bars pivoted in an arcuate array on said segment to strike at a common typing point on the platen, said segment having a dust shelf projecting forwardly therefrom circumjacent the arcuate type-bar pivot array, each of said type bars being arched so as to clear said dust shelf when the type bar types, each of said type bars having an operating arm extending rearwardly and downwardly from its pivot, a series of sub-levers having upstanding lever arms forward of the type-bar pivots, a series of straight pull links connecting the type-bar operating arms and the sub-lever arms, said pull links being each disposed at an appreciable angle from the body of the corresponding type bar so as to afford space for the arched portion of the type bar, said sub-levers being non-case-shiftable, said pull links therefore oscillating during case shift to accommodate the shift movement of the type bars, each

said link having a construction line extending rearwardly from its point of connection on the sub-lever arm and bisecting the angle of oscillation, the arrangement of all the links and sub-lever arms being such that the construction lines of the links converge substantially at a common point, said point of convergence lying in a center-line of the typewriter extending rearwardly from the typing point and passing through the axis of the platen, said point of convergence being in a horizontal line normal to said center-line, and means to guide said segment for case-shift movement in a cylindrical path the axial center of which coincides substantially with said horizontal

5 10 15 20 25 30 35 40 45 50

5. In a typewriter type-action system, a cylindrical platen, a case-shiftable segment, a series of type bars pivoted in an arcuate array on said segment to strike at a common typing point on the platen, said segment having a dust shelf projecting forwardly therefrom circumjacent the arcuate type-bar pivot array, each of said type bars being arched so as to clear said dust shelf when the type bar types, each of said type bars having an operating arm extending rearwardly and downwardly from its pivot, a series of sub-levers having upstanding lever arms forward of the type bar pivots, a series of straight pull links connecting the type-bar operating arms and the sub-lever arms, said pull links being each disposed at an appreciable angle from the body of the corresponding type bar so as to afford space for the arched portion of the type bar, said sub-levers being non-case-shiftable, said pull links therefore oscillating during case shift to accommodate the shift movement of the type bars, each said link having a construction line extending rearwardly from its point of connection on the sub-lever arm and bisecting the angle of oscillation, the arrangement of all of the links and sub-lever arms being such that the construction lines of the links collectively define a conical contour, the apex of which is in a center-line of the typewriter extending rearwardly from the typing point and passing through the axis of the platen, and means to guide said segment for case-shift movement in a generally cylindrical path the axial center of which is on a horizontal line transverse of the typewriter and at or near said conical apex.
